UNITED STATES PATENT OFFICE

ARTHUR B. UTLEY, OF SPRINGFIELD, MISSOURI

SEWER CLEANER

Application filed November 28, 1932. Serial No. 644,633.

This invention relates to improvements in sewer cleaners, particularly a type of cleaner designed to extract matter which clogs water sewers or conduits, especially fibrous roots which are often found to enter water sewers through seams and joints and which after having thus entered continue to grow, forming a fibrous mass which obstructs the flow of sewage through the conduit, causing other matter to collect at this point and finally stopping the flow completely.

This form of obstruction has proven to be one of the most serious to confront the plumbing profession due to the fact that it has been almost impossible to completely clear a sewer of such an obstruction, inasmuch as when attempting to do so with the forms of cleaners in use previous to my invention of the present device it has been difficult to secure a substantial hold upon such a mass of fibrous matter, the result being to tear small bits of the obstruction loose and finally secure a restricted opening through same which allows a flow of sewage temporarily, the fibrous roots remaining in the sewer to grow and accumulate another mass which inevitably clogs the sewer again. Unless the roots are broken loose at the source or entrance into the sewer they will continue to grow and form masses of fibrous obstructions. It is the object of this invention to secure such a substantial hold upon the complete mass of roots that the entire obstruction will be broken loose at its source when extraction is attempted.

It will be noted that my device is so constructed that when contact is made with the obstruction and the device is rotated in the proper direction by twisting the flexible cable to which it is attached the device screws into the mass forming the obstruction which continues to accumulate upon the device until it is filled with a solid, compact mass which will not readily tear or separate in the process of extraction.

It will also be observed that means is provided whereby the device will catch and tear loose from the walls of the sewer any portion of the mass which adheres thereto including

the main branch of roots which forms the source in the case of massed roots.

In my experience with this device I have had it to fasten itself with such security to a large mass of roots which were so tenaciously fastened in the sewer that it was necessary to use a horse on the cable to extract the mass, such efforts resulting in the complete removal of the entire lot of roots.

Ordinarily, without the use of my device it is necessary to dig down and locate the point where the roots enter the sewer and break the sewer at this point to remove the mass and inasmuch as it is usually found that masses of roots have been formed at several separate points in the sewer by the roots having entered at different joints it becomes necessary to do a considerable amount of digging and breaking of the sewer to rid it of these obstructions, with the attendant repair work which follows such operations.

With my invention it is only necessary to gain entrance to the sewer at one point to remove the several obstructions and furthermore, this opening need not be located at the exact point of any obstruction but may be made at any convenient point in the sewer within reasonable distance of the obstruction.

It will also be noted that my device is of a compact form and for use in combination with a flexible cable which permits it being passed through sewers having considerable deviation from a straight line, such as Y branches and $\frac{1}{8}$ th bends which enlarges the scope of its practical use.

Aside from the principal function of this device; i. e., the removal of massed roots from sewers it is useful as a plunger for cleaning sewer traps and hopper closets by screwing it into a piece of burlap or the like forming a swab.

Other objects and advantages of this invention will be pointed out in the detailed description appearing hereinafter, and in order that the invention may be better understood, reference is had to the accompanying drawing in which:

Fig. 1 is a perspective view showing the device which is composed of a hub or central part 1, to which is attached concentrically

wound helical spirals 2 forming screws, the extreme ends (a) of which are pointed. Attached to the central part 1 are curved prongs or spurs 3 extending radially to approximately the same diameter of the spirals 2 and having their extreme ends (b) pointed. I have shown in the present instance the central portion 1 as having a threaded part (c) for attaching to a correspondingly threaded cable-end (4 in Fig. 2), however I am making no claim as to this particular method of fastening inasmuch as my invention does not include the cable to which my device must be attached for operation but am showing this method of attaching as a means of teaching construction and operation of my device. Any other substantial means of connection of this device to the cable would be satisfactory, such as welding, clamping, etc.

Fig. 2 is a horizontal view of the device to which are assigned the same numbers and letters designating the various parts as given to Fig. 1, with the addition of 4 which is the threaded cable-end.

It will be observed that the forward ends of the spirals 2 are sharpened at (a) for easy entrance into the mass of sewer obstruction and the parts forming these spirals should preferably be tapered toward their extreme pointed ends for best operation. The spiral portions 2 and the curved prongs 3 may be welded to the central portion 1.

Fig. 3 shows a sectional view of a sewer in which the device is being attached to a mass of roots. This view also shows the use of the cable in connection with this device. In this view the device is designated by the letter (f), (g) designates the cable, (h) the sewer and (i, i, i) show the masses of fibrous roots which have entered the sewer at the seams. In operation this device is secured to the end of a cable (g) which is flexible enough to make the necessary bends in the sewer and yet rigid enough to withstand sufficient twisting force to operate the device and having made an opening into the sewer at a convenient point the device is inserted into the sewer and pushed along by the cable until it reaches the obstruction after which it is screwed into the mass of obstructing matter

by twisting the cable. This twisting is continued until the obstruction is loosened or until the device has secured a substantial hold upon the obstruction, after which it is withdrawn from the sewer by means of the cable, bringing the obstruction with it. It will be observed that as the parts 2 enter the obstruction the twisting action of the spirals tend to draw the obstruction into a compact mass while the prongs 3 serve to sever from the walls of the sewer any portion of matter which may adhere thereto such as the principal roots in the case of root obstructions. Fig. 3 also shows how an opening is made in the ground (k) and through the sewer (h).

It is obvious that a more secure hold can be obtained upon a mass of roots with this device than with any device employing simple hooks, prongs or spears inasmuch as the spirals in my device operate as an extracting medium throughout their entire length giving the maximum grasp upon the obstruction.

I claim:—

1. A sewer cleaner comprising a central hub having attached thereto a plurality of concentrically wound helical spiral parts forming intertwined screws, said spiral parts having their frontal ends pointed, curved radiating prongs attached to said central hub and having their outer ends pointed, means for securing said central hub to an operating cable whereby said cleaner may be screwed into a sewer obstruction.

2. A sewer cleaner comprising a combination of a plurality of concentrically wound helical screws and a plurality of radiating curved prongs with means for turning same to engage a sewer obstruction.

3. A sewer cleaner comprising a central hub to which is attached a plurality of sharpened rods, said rods being wound into concentric spirals forming screws for engaging sewer obstruction, a plurality of radiating prongs attached to said hub for severing sewer obstructions from sewer walls, means for turning said sewer cleaner, said means comprising a retrieving means therefor.
